ANCHORING PLATE

William J. Koehler, Babylon, N. Y.

Application June 6, 1952, Serial No. 292,023

2 Claims. (Cl. 214—10.5)

This invention relates generally to securing members and particularly to an anchoring device for disposition between bodies or containers which are stacked one upon another to prevent the relative lateral movement thereof.

Among its other objects the present invention contemplates a device which will positively maintain bodies in stacks or tiers while being moved or transported from place to place, as well as while stacked for storage.

To these ends the instant invention proposes a plate adapted to be attached to one of a tier or stack of bodies or containers and having a multiplicity of projections or teeth arranged to be imbedded in a fixed component of the next adjacent body or container in the stack or tier. This interengagement between the plate fixedly attached to one body or container and a component of the next adjacent body or container effectively prevents any relative movement between such bodies or containers in parallel planes and yet permits them to be readily separated and said interengagement broken when this is desired.

With the above and other objects in view, as will be apparent, this invention consists in the construction, combination, and arrangement of parts all as hereinafter more fully described, claimed and illustrated in the accompanying drawings, wherein:

Fig. 1 is a perspective view of a securing or anchoring device constructed in accordance with the teachings of this invention;

Fig. 2 shows the present device applied to a plurality of containers stacked in multiple tiers and illustrates the manner in which it prevents relative parallel movement between the containers in a tier; and

Fig. 3 is a perspective view of the device of Fig. 1 attached to a container showing it as employed in Fig. 2.

While the instant invention may be adapted for general application in counteracting relative parallel movement of stacked bodies or containers of any type both for storage and transportation, it has particular utility in stacking bodies or containers which are round or other than rectangular in cross-section for transportation. One example of this type of body or container is that employed in the handling and shipment of engines.

Due to the nature and complexity of modern engines and especially aircraft engines, the design and construction of the containers in which these engines are shipped involves skill and expense to provide for the factors that must be considered and compensated for such as weight, corrosion, etc. It is, therefore, desirable to use and reuse these containers as often as possible. Such use and reuse of this type container, as well as the size of the container, gives rise to a transportation problem, viz., the number of freight cars that is required to transport any given number of these containers filled and empty because heretofore only one layer or course of containers, empty or filled, has been loaded on each car. By using the present device two and sometimes more layers or courses of containers may be loaded on a single car thereby reducing the number of cars required by at least half.

At present, with the standard freight car, it is only

2

possible to safely handle six or eight of these containers per car, since prior to this invention no means was available to permit the stacking or tiering thereof. It is, therefore, the primary purpose of this invention to provide a means whereby containers of the type mentioned and others as well may be stacked in tiers or layers on conventional flat cars without danger of relative parallel movement during shipment. In this way the number of containers per car may be, and is, at least doubled.

10 Reference being now had more particularly to the drawings the numeral 10 designates a container of the type presently employed for the storage and shipment of engines. These containers or tanks 10 are preferably of metal construction and are cylindrical in shape. They 15 comprise a pair of identical halves 11 each of which is substantially semi-circular in cross-section. An angle 12 defines the outer surface of each container half 11 adjoining the edge or lip thereof to which it is affixed, as by welding or the like, thereby creating a lateral flange 13 which projects outwardly of said edge or lip and completely encircles the container half. The flange 13 is provided with a number of holes regularly spaced one from another to the end that when two container halves 11 are brought together with their respective flanges 13 20 in abutment the holes of one flange will align with those of the other. In this way the two halves 11 can readily be connected and assembled into the final container 10 by means of the bolts 14 which transpierce the holes thus provided in the flanges 13.

25 While other methods may be employed for the assembly or connection of the container halves 11 that above-described is the one presently being used. An airtight joint is desired between the sections 11 so that the engine stowed in a container 10 may be said to be vacuum-packed. To this end a rubber gasket or seal 15 is interposed and held between the flanges 13.

30 In order to facilitate the handling of each assembled container 10 and the maintenance thereof in the proper position the lower container half 11 thereof is equipped 35 with a base platform or frame 17. This frame 17 preferably consists of a series of transverse strips 18 welded or otherwise secured to the bottom of the container and several longitudinal, inwardly faced angles 19 which extend the full length of the container 10, and one affixed 40 to the extremities of the several strips 18. A number of vertical bracket plates or braces 20 are aligned on each 45 side of the lower container half 11 and are welded or otherwise affixed at their ends to the wall of said container half and to the associated angle 19. Thus a cradle is 50 established in which the lower half 11 of the tank 10 is permanently mounted.

55 A wooden runner or skid 21 is secured, as by the bolts 22, to the undersurface of each angle 19, and it is the bottom surfaces of these skids 21 which support container 10. The handling or movement of the container 10 is 60 facilitated and made easier and safer by the skids 21, and the container per se is protected against damage.

65 The above-described container per se forms no part of the present invention but is illustrative of a common, present day container employed for the purposes set forth. Hence, the particular construction described hereinabove 70 may be extensively modified or varied without affecting or limiting the scope of this invention.

As already pointed out this invention contemplates the stacking of bodies in tiers and the retention thereof so stacked. To this end each upper container half 11 is provided with at least two peripheral flanges 23, one affixed or secured to the container half near each end thereof. Each of these flanges 23 terminates in a transverse rim 24 resting substantially parallel to the container 75 wall. The end edges of angular bracket plates 25 are

medially welded or otherwise immovably secured to the rim 24, one on either side of the longitudinal axis of the container 10 in such a way that one section of each of said bracket plates lies in a horizontal plane while the other section thereof rests in a vertical plane. Both plates 25 associated with each rim 24 rest in planes substantially tangential to the container 10; hence the upper faces of the four or more bracket plates 25 of each container are disposed in one horizontal plane thereby creating, in effect, a platform to coat with the skids 21 of a second or superposed container 10 thereby providing means to support the upper container on the lower. Manifestly, the upper container 10, when thus stacked, rests solely on its skids 21 which lie in flush abutment against the horizontal sections of the brackets 25. Moreover, in this position all of the containers in the one stack must be disposed in the same vertical plane.

However, as additional containers 10 are stacked, or when it is desired to transport two or more layers or courses of containers while stacked as above described, it is necessary to anchor or secure the several containers in a stack or tier one to the other against relative parallel movement. Since the anchoring or securing of the first or lower containers 10 to the ground or floor in case it is desired to store the containers or to the bed of a vehicle in case it is desired to transport them presents comparatively no problem, the instant invention contemplates the use of any one of the well-known and extensively employed chocks and other means for this purpose. It is to the attachment or fixation of the upper container or containers to the underlying container or containers that the instant invention directs itself.

To that end this invention proposes a relatively thin, metallic plate 26 having a relatively large number of integral claws or teeth 27 projecting from one face thereof. These teeth 27 can be each created by making a pair of intersecting or cross cuts in the plate 26 and bending back that portion of the plate which defines said cuts to a position substantially normal to the face of the plate. In this manner either a tooth having a single spur or, as is preferred, a tooth having four individual spurs may be created for every pair of intersecting cuts. It is to be noted that all the teeth 27 project outwardly from the same face of the plate 26 so that the opposite face of said plate remains smooth or flat.

Along one of its edges the plate 26 is provided with a pair of integral ears 28 which lie in the same plane as the plate 26 but that portion of said plate defining these ears extends laterally beyond the toothed area of the plate. The outer end portions of the ears 28 are rebent angularly in opposition to the projecting teeth 27 to create a pair of spaced, channeled lips 29 which open toward the flat or smooth face of the plate 26. These lips 29 are arranged to span the rim 24 of a flange 23 and to receive the inner edge of the horizontal section of one of the adjacent bracket plates 25 and thereby attach the inner edge of the plate 26 to the corresponding edge of the bracket plate. A plate 26 is placed on each of the four or more angular brackets 25 of every lower or underlying container 10 with the smooth faces thereof in flush abutment with the horizontal surfaces of said brackets and the teeth 27 of each plate projecting upward. At the same time the inner edge of the horizontal surface of each bracket 25 is received in the channeled lips 29 of the plate 26, said lips 29 being disposed on either side of the flange 23 with the rim 24 of said flange snugly received within the space which separates said lips. It may, therefore, be said that the plates 26 are each immovably mounted on, so as to become, in effect, an integral part of, its associated bracket and hence the lower tier container itself.

To insure the immovable attachment of the ends of each plate 26 to its associated bracket 25 both of its ends when installed extend beyond the corresponding edges of

the associated bracket. This permits the extended ends to be bent downwardly and inwardly whereby they engage the under surface of the bracket 25 at its opposite edges. In furtherance of this flexing of the end portions of the plate 26, at least one medial slot 30 may be provided therein, one in each of these ends of the plate 26 thereby forming several ears to engage under the edges of the bracket plate 25.

With the anchoring or securing plates 26 thus positioned one on each of the brackets 25 of every underlying container, the next upper container is disposed upon the standing teeth 27 of plates 26 which then become embedded in the skids 21 of the upper container. All lateral or parallel movement of the upper containers relative to underlying containers is thereby eliminated. Following or repeating this practice many containers can be arranged in tiers or stacks, the container of each being disposed in the same vertical plane.

It is to be noted that the present invention is concerned primarily with the elimination of relative lateral movement between the stacked containers. In instances where the weight or mass of the containers 10 is not sufficient to retain the stack or stacks against relative vertical displacement, additional means such as straps or slings might be employed in conjunction with the anchoring plates. In this case the straps or slings are tightly drawn around a group or stack of containers and fixed at each of its ends to the deck or floor on which the stacked containers are placed so as to eliminate the possibility of vertical displacement of the containers 10 and thereby supplement the instant securing devices.

What is claimed is:

1. An anchoring device comprising a substantially rectangular plate having a plurality of upstanding integral claws each terminating in a plurality of points and projecting from one face only thereof, a pair of integral lips spaced a predetermined distance one from the other and depending from one edge only of said plate, and a pair of ears integrally extending from both ends of the plate, said ears being adapted to be bent in the direction of the lips aforesaid whereby they cooperate with said lips in clampingly engaging the plate to an associated supporting structure.
2. A device for anchoring one body against lateral movement relative to another like body comprising a substantially flat plate to be disposed between said bodies and having a number of claws struck from one face thereof to engage one of said bodies, a pair of spaced channelled lips integrally formed along one edge of said plate, and a pair of spaced ears integrally projecting from at least one of the remaining edges of said plate, said ears being adapted to be bent laterally relative to the plate in the direction of and towards the lips aforesaid to thereby clampingly cooperate with said lips whereby the plate is secured to the other of said bodies.
